UNITED STATES PATENT OFFICE.

ROBERT CORNELY, OF PARIS, FRANCE.

MACHINE FOR FIXING SPANGLED MATERIAL TO TEXTILE FABRICS.

SPECIFICATION forming part of Letters Patent No. 700,305, dated May 20, 1902.

Application filed November 7, 1901. Serial No. 81,468. (No model.)

To all whom it may concern:

Be it known that I, ROBERT CORNELY, a resident of Paris, France, have invented a new and useful Machine for Fixing Spangled Material to Textile Fabrics, which is fully set forth in the following specification.

This invention relates to the class of sewing or embroidering machines in which cording or analogous material is secured to fabric by means of a thread wound around said material and around the thread of stitching formed on the fabric. The machines heretofore devised for this purpose, although adapted for securing cord and even beaded work to fabrics, cannot be successfully used with spangle-work. By my present invention I provide a machine which may be used for successfully attaching spangled material to fabric in the manner indicated.

20 The invention will be readily understood upon reference to the accompanying drawings, illustrating the preferred embodiment thereof, and wherein—

Figure 1 is an elevation, partly in section, of spangled material such as may be attached to fabric by the machine of my present invention. Fig. 2 is a top plan and Fig. 3 a bottom plan view of said spangled material. Fig. 4 is an enlarged view, partly in section, of the lower end of the nipple-tube and associated parts, showing the manner in which the same act in attaching the spangled material to the fabric. Fig. 5 is a sectional view through the lower part, and Fig. 6 a similar view through the upper part, of the nipple-tube and associated parts. Figs. 7 to 10 are detailed views of parts hereinafter referred to.

The spangled material is composed of single round (or otherwise shaped) flat spangles 40 A, which are threaded on a thread b. This thread b is secured to one or more thin cords d by means of a thread g, Figs. 1 and 3, which passes between the spangles and is wound around the thread b and the cord d. This kind of spangle material is produced in well-known manner on special passementerie-machines and can be varied according to the arrangements to these machines.

The principal feature of this machine is the 50 hollow needle-bar E, secured in the tube L of the machine and acting not only to lead the spangled material from the bobbin to the nip-

ple, but also to prevent said material from twisting and turning during its passage through said bar, so that the spangles reach 55 the cloth exactly in the same arrangement as they come from the spool. Leaving the needle-bar E the spangles traverse the guide a of the nipple, from which they pass to the cloth H.

The spangled material is wound upon a bobbin M, disposed above the needle-bar E, Fig. 6, in such a manner that when it passes through the needle-bar E every spangle is directed in a downward position, as shown at 65 Figs. 4 and 6.

The thread-carrier K winds its thread G around the thread D of the seam and around the cord or cords d, which hold the spangles; but this work will only be perfect if the thread 70 G is always passed in the space between the spangles A, Fig. 4. It is for this reason that, as above stated, the spangle material must be wound upon the bobbin M in such a manner that the spangles A must assume the inclination shown in Fig. 4 when passing through the needle-bar E, in consequence of which when they reach the cloth the spangles come in the proper position to permit the thread G of the thread-carrier K to pass into the space 80 between the spangles, which would not be the case if the spangles were not presented in this manner.

In order to permit the spangles to move freely when passing from the bobbin M and 85 through the needle-bar E and to prevent them from coming into contact with the edge of or catching said needle-bar, which would occasion imperfect work, a guiding cylinder or roller n is arranged in such a manner that 90 the spangled material is introduced at the center of the needle-bar without touching the edge of the same. To assure this, the upper end of needle-bar is funnel-shaped. In consequence of the elongated outline of a horizontal section of the spangle material the passage through the needle-bar E must have a similar elongated shape in order to prevent turning or twisting of said material during its passage through the needle-bar. This 95 needle-bar has therefore in this particular instance an oval section, as shown at Fig. 10, and of course the passage through guide a of nipple C must have a similar section.

The needle-bar E in the tube L, which is cylindrical, as usual, is secured by means of a sleeve m, Figs. 7, 8, and 9, which is provided with two thin and flexible legs 2. The oval needle-bar E is passed through the central opening 3 of sleeve m, and by turning the screw o the upper end of the tube L, which is split at one side from opening m' upward, (see dotted line, Fig. 6,) as well as the legs 2, 10 are compressed, and the tube E is thus securely fixed in tube L.

It is evident that the invention may be used with a sewing or embroidering machine working with a threaded needle instead of a hook-15 needle.

What I claim is—

1. In a sewing or embroidering machine for attaching spangled material to fabric, the combination with stitch-forming mechanism 20 of a passage or conduit through which the spangled material passes to the fabric, said conduit being of elongated cross-section to prevent the spangled material from becoming twisted and to present the same in proper position for the binding-thread to pass between the spangles, and a thread-carrier passing a binding-thread around the spangled material between the spangles and around the stitches formed by the stitch-forming mechanism.
2. In a sewing or embroidering machine for 25 attaching spangled material to fabrics, the combination with a hollow needle-bar through which the spangled material is adapted to pass, a needle carried thereby and coöperating

stitch-forming mechanism, of a hollow nipple 35 below the needle-bar through which the spangled material passes from the needle-bar to the fabric, the passage through the needle-bar and nipple being of elongated cross-section to prevent the spangled material from 40 becoming twisted and to present the same in proper position for the binding-thread to pass between the spangles, and a thread-carrier passing a binding-thread around the spangled material between the spangles and around 45 the stitches formed by the stitch-forming mechanism.

3. In a sewing or embroidering machine for attaching spangled material to fabrics, the combination with a hollow needle-bar, a needle 50 carried thereby and coöperating stitch-forming mechanism, of a reel above said bar on which the spangled material is wound, a roller or pulley over which the spangled material passes to the passage through the needle-bar 55 which is of elongated cross-section to prevent the spangled material from becoming twisted, and a thread-carrier passing a binding-thread around the spangled material between the spangles and around the stitches formed by 60 the stitching-forming mechanism.

In testimony whereof I have signed this specification in the presence of two subscribing witnesses.

ROBERT CORNELY.
